ELECTRIC SWITCH

Waldo J. Kelleigh, Wayland, Mass., assignor to
General Control Company, Cambridge, Mass., a
corporation of Massachusetts

Application August 4, 1943, Serial No. 497,314

8 Claims. (Cl. 200—1)

1

This invention relates to electric switches and more particularly switches of the so-called telephone type adapted to be mounted in a switchboard panel with nothing but the handle or key projecting from the face of the board, each switch comprising a frame, a contact block, a plurality of groups of contact springs mounted on the block and an actuator for operating the contacts.

Objects of the present invention are to provide a switch which is simple and economical to manufacture, which is durable and reliable in use, which can be readily converted from a locking type in which the key remains in operative position until returned to neutral position to the non-locking type in which the key remains in operative position only so long as it is held in that position by hand, which has a long life, which electrostatically shields opposite groups of contacts from each other, which is self-aligning in the process of assembling the parts together, and which is generally superior to prior switches of the character referred to.

In one aspect the invention involves a frame having a supporting wall with a group of spring contacts mounted on one side of the wall and an actuator movably mounted on the other side of the wall, the actuator having a roller or other operator extending through an opening in the wall for operating the contacts, and a spring-actuated detent mounted on the first side of the wall for engagement with the actuator through an opening in the wall yieldingly to hold the actuator in one or more of the positions to which it is moved.

In a more specific aspect the invention involves two walls with a space therebetween for the aforesaid actuator and with a support for switch contacts on both sides of the juxtaposed walls. When employing two frame plates a spring-actuated detent is preferably provided on each plate, the two detents pinching the actuator therebetween through openings in the plates. By providing a detent on each side the thrusts of the two detents tend to counteract each other thereby reducing the friction and wear on the pivot pin of the actuator or other part which controls its path of movement. By making the actuator of variable thickness along the zone engaged by the detents the actuator is yieldingly held in predetermined positions, as for example a neutral central position and an operating position on one or both sides of the neutral position. By providing the detents with rollers for rolling engagement with the actuator the friction is reduced, thereby making the switch easier to operate and

2

prolonging its life. By providing coil springs instead of leaf springs for actuating the detents the springs are less expensive, last longer and can be replaced more readily and economically. In the preferred construction the thrusts imparted to the opposite sides of the actuator by the detent springs automatically equalize. Thus the springs have no tendency to tip the actuator and consequently the actuator operates with less friction.

10 In still another aspect the invention involves a frame having two legs with a space therebetween and a contact block fitted into the space with grooves in one or both sides of the block to receive one or both of the legs. The contact block is preferably fastened on the frame by means of a screw or other fastener extending through the block lengthwise of the legs into engagement with the frame. When the frame is in the form of two plates as aforesaid, the plates are held together by the grooves in the contact block, and by making a fairly snug fit between the block and plates the parts are self-aligning when the block is slipped into the slots in the plates.

For the purpose of illustration a typical embodiment of the invention is shown in the accompanying drawing in which

Fig. 1 is a side elevation;
Fig. 2 is an end elevation;
Fig. 3 is a section on line 3—3 of Fig. 1;
Fig. 4 is a bottom view;
30 Fig. 5 is a section on line 5—5 of Fig. 1;
Fig. 6 is a perspective view of the actuator;
Fig. 7 is a perspective view of one of the spring detents;

35 Fig. 8 is a side elevation of a slight modification; and

Fig. 9 is a section on line 9—9 of Fig. 1.

The particular embodiment of the invention chosen for the purpose of illustration comprises 40 two frame plates 1 and 2 which are offset at 3 so that, with their lower ends abutting each other face to face, the upper ends are separated by a space 4, the tips of the upper ends being bent outwardly to form flanges 6 and 7 for mounting 45 the switch on a switchboard or the like. The upper ends of the plates may be interconnected by rivets 8 and the lower ends may also be riveted together as indicated at 9. Extending upwardly from the bottom edges of the frame plates are 50 slots 11 (Figs. 1 and 4) dividing the frame into two legs, and mounted in these slots is a contact block 12, the opposite sides of the block having grooves to receive the edges of the slots. From the upper ends of the slots 11 to the shoulder 3, 55 the plates are pressed outwardly as indicated at

13 to form opposing grooves which together form a cylindrical socket. After the plates are secured together this socket is threaded to receive a screw 14 which extends through a vertical opening 16 in the block 12 and then threads into the socket.

10 Mounted on the opposite sides of the contact block 12 are four groups 21, 22, 23 and 24 of contact springs, the springs being held by screws 26 with a layer 27 of insulation on each side of each spring. The heads of the screws seat on a plate 28 and the other ends of the screws are threaded into a plate 29. In the illustration each group of contact springs comprises a central spring which is somewhat longer than the other two springs and which is engageable with either of the other two springs. As shown in the drawing the center spring usually contacts with the inner spring when the key is in the central neutral position shown in Figs. 1 and 3 and, when the key is moved to one of its operative positions, the central spring is moved out of contact with the inner spring into contact with the outer spring.

15 The actuator for operating the contact spring comprises a cam plate 31 which is pivotally mounted in the space 4 by means of a pivot pin 32. The upper edge of the cam plate is provided with a threaded extension 33 to receive the handle 34. Mounted in opening 36 in the cam plate are tubes which project laterally through the arcuate slots 38 in the plates 1 and 2. Mounted on the projecting ends of the tube are rollers 41 for operating the middle springs of the groups, the rollers being held on the tubes by means of screws 42 threaded into the ends of the tubes. The actuator is also provided with an opening 43 (Fig. 1) to receive a stop pin for use in the event that it is desired to prevent movement of the actuator in one direction (counterclockwise in Fig. 1). By omitting the pin 44 the key 34 may be thrown either to the right or to the left.

20 For the purpose of holding the actuator in its central position or in its right or left operating position, the lower end of the plate 31 is shaped so that it is thin in the middle 46 and at the ends 47, but relatively thick in between, the thickness varying gradually from minimum to maximum and vice versa. Mounted on the outside of the lower end of the plate 22 are detent holders 51 having legs 52 which straddle the raised portions 13 of the plates 1 and 2. At their upper free ends the detent holders are provided with openings 54 to accommodate the rollers 56 which rotate on pins 57 seating in the semi-circular recesses 58 above and below the openings 54. The detent 25 holders are pressed inwardly by coil springs 71 (Fig. 9), the inner ends of the springs bearing on the outer faces of the holders and the outer ends of the springs reacting against a reactor which, in the illustration, comprises a pin 72 having heads on its opposite ends and washers 73 between the heads and springs. The pin slides freely in a sleeve 74 which extends through openings in the plates 1 and 2 and openings 75 (Fig. 7) in the detent holders, the sleeve being fast to the plates 1 and 2 but fitting the openings 75 loosely.

30 Thus the lower end of the actuator is pinched between the rollers 56, the holders 51 substantially meeting the outer faces of the plates 1 and 2 when the rollers 56 engage parts 46 and 47 of minimum thickness and springing outwardly as 35 the rollers ride over the thicker parts of the actuator. Thus the actuator is yieldingly held in the mid-position or in either one of the operative positions. By virtue of the spring arrangement the lateral thrusts of the detents on the actua-

35 tor are balanced and there is no tendency to tip the actuator out of its plane of movement. In this way friction is minimized, whereby the actuator moves with ease and with little wear.

40 The plates 1 and 2 are provided with opposed openings 61 and 62 for use in the event that it is desired to prevent the actuator from moving far enough to the right or left to be held in operative position by the spring detent. Thus Fig. 8 shows a rivet 63 in the opening 62 for limiting the movement of the key 34 to the left. Thus when the key is released it returns to neutral position instead of remaining in the left-hand operative position.

45 From the foregoing it will be understood that the modification shown in Fig. 8 differs from the construction of the preceding figures only in that a rivet 63 has been mounted in the opening 62. It will be evident that by making the frame 50 1—2 of metal it electrostatically shields the two groups of contacts 21 and 22 from the two groups 23 and 24, thereby avoiding interference between the currents in the circuits on opposite sides of the switch. By virtue of the double-plate construction a very rigid frame can be made with 55 relatively thin stock. This construction also affords a convenient and effective way of mounting the actuator 31, namely by an ordinary rivet so as to be self-centering without providing shoulders on the rivet. By virtue of the telescope interengagement between the switch block and the frame plates the parts are self-aligning in the process of manufacture and after being assembled the engagement of the edges of the frame 60 plates in the grooves of the switch block 12 serve to hold the two plates together. The unique construction also permits the parts to be held together by the single screw 14. Moreover both the actuator and the contact block are simple in 65 shape and economical to manufacture. For example, the actuator may be coined and the block may be die cast. By pinching the actuator between two spring detents the thrusts of the detents counteract each other and by providing the 70 rollers 56 the friction and wear are minimized. The openings 61 and 62 and the pins or rivets 63 afford a convenient way of changing a switch from the locking to the non-locking type and vice versa. For example, the switches may be carried in stock without pins 63 and then, in those 75 switches to be made non-locking, pins 63 may be inserted. Likewise the keys may be readily changed from two-way to one-way operation by inserting pins in the openings 43.

55 It should be understood that the present disclosure is for the purpose of illustration only and that this invention includes all modifications and equivalents which fall within the scope of the appended claims.

60 I claim:

1. An electric switch comprising contacts, a contact actuator movable from a normal position to an advanced position, detents engaging opposite sides of the actuator for holding it in advanced position, a spring reactor extending transversely of the actuator adjacent thereto, the reactor having an abutment outside each detent, and a compression spring outside each detent, each spring being interposed between one of said abutments and one of said detents, said reactor being free to move transversely of the actuator, whereby the thrusts of said springs against said detents are automatically equalized.

2. An electric switch comprising contacts, a contact actuator movable from a normal position

to an advanced position, detents engaging opposite sides of the actuator for holding it in advanced position, a pin extending transversely of the actuator adjacent thereto, the pin having an abutment outside each detent, and a compression spring outside each detent, each spring being interposed between one of said abutments and one of said detents, said pin being free to move transversely of the actuator, whereby the thrusts of said springs against said detents are automatically equalized.

3. An electric switch comprising contacts, a contact actuator movable from a normal position to an advanced position, detents engaging opposite sides of the actuator for holding it in advanced position, a pin extending transversely of the actuator through openings in said detents, the pin having an abutment outside each detent, and a compression spring outside each detent, each spring being interposed between one of said abutments and one of said detents, said pin being free to move transversely of the actuator in said openings, whereby the thrusts of said springs against said detents are automatically equalized.

4. An electric switch comprising contacts, a contact actuator movable from a normal position to an advanced position, detents engaging opposite sides of the actuator for holding it in advanced position, a sleeve extending through openings in said detents and fitting loosely therein, means for supporting the sleeve intermediate the detents, a pin extending through said sleeve and projecting from each end thereof, the pin having an abutment beyond each end of the sleeve, and a compression spring surrounding the pin outside each detent, each spring being interposed between one of said abutments and one of said detents, said pin being free to slide lengthwise in said sleeve, whereby the thrusts of said springs against said detents are automatically equalized.

5. An electric switch comprising a frame having two juxtaposed walls with a space therebetween, a group of spring contacts mounted outside each wall for movement relatively thereto, an actuator mounted in said space for movement parallel to the walls, switch operators extending from the actuator through openings in said walls for operating said groups respectively, spring-actuated detents mounted outside said walls for engagement with opposite sides of said actuator through openings in the walls yieldingly to hold the actuator in one or more of the positions to which it is moved, a pin extending transversely of the actuator through openings in said detents and said walls, the pin having an abutment outside each detent, and a compression spring outside each detent, each spring being interposed between one of said abutments and one of said detents, said pin being free to move transversely of the actuator in said openings, whereby the thrusts of said springs against said detents are automatically equalized.

6. An electric switch comprising a frame having two juxtaposed walls with a space therebetween, groups of spring contacts mounted outside each wall for movement relatively thereto, an actuator mounted in said space for movement parallel to the walls, switch operators extending from the actuator through openings in said walls for operating said groups respectively, spring-actuated detents mounted outside said walls for engagement with opposite sides of said actuator through openings in the walls yieldingly to hold the actuator in one or more of the positions to

which it is moved, a sleeve extending through openings in said detents and walls, the sleeve fitting the wall openings tightly but being loose in the detent openings, a pin extending through said sleeve and projecting from each end thereof, the pin having an abutment beyond each end of the sleeve, and a compression spring surrounding the pin outside each detent, each spring being interposed between one of said abutments and one of said detents, said pin being free to slide lengthwise in said sleeve, whereby the thrusts of said springs against said detents are automatically equalized.

7. An electric switch comprising two juxtaposed plates which are offset intermediate their ends to abut each other at their lower ends and provide a space therebetween at their upper ends, an actuator mounted in said space to swing parallel to the plates about a transverse axis, groups of spring contacts mounted on the outside of said plates with their free ends adjacent said space, switch operators extending from the actuator through openings in the plates for operating said groups, said actuator having a handle extending upwardly beyond said walls and a tail having recesses in its opposite sides, rolling detents engageable with said recesses through openings in said upper ends of the plates to hold the actuator in different positions, holders for the detents mounted on the outside of said lower ends, a pin extending transversely of the actuator through openings in said holders and the lower ends of said plates, the pin having an abutment outside each holder, and a compression spring outside each holder, each spring being interposed between one of said abutments and one of said holders, said pin being free to move transversely of the actuator in said openings, whereby the thrusts of said springs against said holders are automatically equalized.

8. An electric switch comprising two juxtaposed plates which are offset intermediate their ends to abut each other at their lower ends and provide a space therebetween at their upper ends, an actuator mounted in said space to swing parallel to the plates about a transverse axis, groups of spring contacts mounted on the outside of said plates in offset relation to the vertical plane containing said axis, switch operators extending from the actuator through openings in the plates for operating said groups, said actuator having a handle extending upwardly beyond said walls and a depending tail having recesses in its opposite sides, rolling detents engageable with said recesses through openings in the upper ends of said plates to hold the actuator in different positions, holders for the detents mounted on the outside of said lower ends, said detents and holders being disposed in the region of said plane, a sleeve extending through openings in said holders and said plates, the sleeve fitting the plate openings tightly but being loose in the holder openings, a pin extending through said sleeve and projecting from each end thereof, the pin having an abutment beyond each end of the sleeve, and a compression spring surrounding the pin outside each holder, each spring being interposed between one of said abutments and one of said holders, said pin being free to slide lengthwise in said sleeve, whereby the thrusts of said springs in said holders are automatically equalized.

WALDO J. KELLEIGH.
